UNITED STATES PATENT OFFICE.

WILHELM SCHLICH, OF DUSSELDORF-OBERKASSEL, GERMANY

COUNTING APPARATUS FOR COINS AND CHECKS.

1,001,895.

Specification of Letters Patent. Patented Aug. 29, 1911.

Application filed December 30, 1910. Serial No. 600,959.

To all whom it may concern:

Be it known that I, WILHELM SCHLICH, a citizen of Germany, and residing at Dusseldorf-Oberkassel, Germany, have invented a new and Improved Counting Apparatus for Coins and Checks, of which the following is a specification.

This invention relates to an apparatus of novel construction for marshaling coins, checks or similar devices into stacks containing a pre-determined number thereof, so that the coins are disposed of in an orderly manner, and may be readily counted.

In the accompanying drawing: Figure 1 is a longitudinal section of an apparatus embodying my invention; Fig. 2 a plan; Fig. 3 a rear view of the chute; Fig. 4 a bottom view thereof; Fig. 5 a longitudinal section of a modification of the apparatus; Fig. 6 a plan thereof; Fig. 7 a cross section; Fig. 8 a similar section showing the parts in a different position, and Fig. 9 a detail of the bipartite coin tube.

The apparatus comprises essentially two component parts viz: a chute adapted to receive the coins, and a box over which the chute is movable, and within which the coins are piled up into a number of separate stacks.

10 The chute consists of a hopper *b* provided at its lower end with a tongue *d* which checks the discharge of the coins into a tube *a* within which they become piled up. Tube *a* is open at its bottom, and is here provided 15 with a pair of pivoted jaws *e*, *f* having handles *g*, and influenced by springs *g* which tend to project the jaws beneath said open bottom to form a coin rest. Intermediate jaws *e*, *f*, tube *a* is provided with a 20 pair of parallel guides *c* that extend slightly beneath said jaws, and also with a tooth *z* which does not project down quite as far as the guides and constitutes a pusher for the coins.

15 The box *h* is provided with a number of tapering transverse ribs *i*, separated by intervening shallow grooves or recesses *i* which are adapted for the reception of successive coins. The height of ribs *i* is somewhat less than the thickness of the coins, so that the latter when seated within the grooves project slightly above the ribs. Longitudinally over box *h* extend a pair of rails *v*, having a clearance above each groove *i* and adapted to be engaged by the guides *c* of the coin chute. Beyond rails *v* each

groove *i* opens into a pocket *k* of considerable depth and within which the coins are adapted to be stacked. The pockets on one side of the box are of less diameter than those on the other side, so that the apparatus is adapted for assembling larger as well as small coins. Near one end of box *h* there is centered between rails *v* an abutment *m* adapted to enter grooves *l* of tube *a* when the coin chute arrives at the end of its race.

In use the guides *c* of the coin charged hopper are brought into engagement with rails *v*, and jaws *e*, *f* are withdrawn so that the coins within the hopper will be supported upon the top of box *h*. The hopper being moved along the box, the bottom coins will successively drop into consecutive grooves *i*, so that each groove becomes charged. When the hopper has passed over the active portion of the box, any coins remaining in the hopper will be slightly lifted by abutment *m*, so that upon a release of handles *g*, jaws *e*, *f* will again close the chute, and permit the same to be lifted off the box without spilling its charge. After the hopper has been disconnected from the box, the latter is tilted sidewise, so that the coins will glide into their pockets *k*, the box being tilted in one direction for larger coins and in the other direction for smaller coins.

The operation described is repeated until the supply of coins has become exhausted, or until all the pockets have become charged. At its bottom, each row of pockets is closed by a slide *y*, upon the withdrawal of which, and the subsequent raising of the box, all coins will be deposited in orderly stacks upon a table or other support. If desired a portion only of the pockets may be emptied, by but partly withdrawing the slide, while a scale may be formed on the slide, which permits it to be set to a given number of coins. So also the pockets may be slotted and graded, so that the number of coins assembled therein may be readily inspected.

In Figs. 5-9, box *h* is provided between rails *v* with a number of openings or recesses *o*, adapted to be closed at their bottom by lids *n*. The latter are fast on a common shaft *p* which by spring-influenced lever *s* and link *u* are connected to handle *w*. Link *u* is further connected by rod *x* to one arm of an elbow lever *z*, the other arm of which actuates a suitable counting mecha-

nism *q*. Upon depressing handle *w*, all lids *n* are opened to discharge the coins while the counting mechanism is simultaneously advanced. Beneath each opening *o* is located a 5 bipartite pocket composed of a pair of semi-tubular shells *k*¹, *k*². Of these, shells *k*² are overlapped at their edges by shells *k*¹, so that by sliding the latter outward, the pockets may be readily emptied. Shells *k*¹ extend above shells *k*² and have inclined upper edges which permit the play of lids *n*.

Along one side of box *h* is arranged a trough *j* which communicates with openings *o* by clearances formed in the intervening 15 rail *v*. After the openings *o* have been charged with the coins, the apparatus is tilted sidewise, so that the coins slide into the trough from which they drop into the hand by next tilting the apparatus endwise. In 20 this way a small number of coins may be segregated and counted.

I claim:

1. In a device of the character described, a box having a plurality of recesses and 25 pockets communicating therewith, combined with a chute slidable along the box and having an open bottom, and a movable coin rest beneath said bottom.

2. In a device of the character described, 30 a box having a plurality of ribs, recesses between the ribs and pockets communicating with the recesses combined with a chute slidable along the box and having an open bottom, and jaws adapted to be projected 35 beneath said bottom.

3. In a device of the character described, a box having a plurality of ribs, recesses between the ribs, pockets communicating with the recesses and rails extending over the ribs 40 combined with a chute having an open bottom, a pair of guides adapted to engage the rails, and jaws adapted to be projected beneath said bottom.

4. In a device of the character described, 45 a box having a plurality of ribs, recesses between the ribs, pockets communicating with both ends of said recesses, the pockets on one side of the box being of greater diameter than those on the other side, combined with 50 a chute slidable along the box and having an open bottom and a movable coin rest beneath said bottom.

5. In a device of the character described,

a box having a plurality of ribs, recesses between the ribs, pockets communicating with 55 the recesses, and an abutment near one end of the box, combined with a chute slidable along the box and having a slot adapted to accommodate the abutment, and jaws adapted to be projected beneath the lower open 60 end of the chute.

6. In a device of the character described, a box having a plurality of ribs, recesses between the ribs, pockets communicating with 65 the recesses and slides adapted to close the pockets, combined with a chute slidable along the box and having an open bottom and a movable coin rest beneath said bottom.

7. In a device of the character described, a box having a plurality of ribs, recesses between the ribs, pockets below the recesses, and lids between the recesses and pockets, combined with a chute slidable along the box 70 and having an open bottom, and a movable coin rest beneath said bottom.

8. In a device of the character described, a box having a plurality of ribs, recesses between the ribs, pockets below the recesses, a series of lids between the recesses and pockets, a shaft on which said lids are 80 mounted, a handle and a counting mechanism operatively connected to the shaft combined with a chute slidable along the box and having an open bottom, and a movable coin rest beneath said bottom.

9. In a device of the character described, a box having a plurality of ribs, recesses between the ribs and adjustable bipartite pockets communicating with the recesses combined with a chute slidable along the box 90 and having an open bottom and a movable coin rest beneath said bottom.

10. In a device of the character described, a box having a plurality of ribs, recesses between the ribs and pockets communicating 95 with the recesses combined with a chute slidable along the box and comprising a hopper, a tongue within the hopper, a tube beneath the tongue, and a jaw adapted to be projected beneath the lower open end of the 100 tube.
